STOP MOTION FOR COMBERS AND THE LIKE

Joseph Fossel, Grafton, Mass., assignor to Alsatian Machine Works, Ltd., Boston, Mass., a corporation of Massachusetts

Application June 10, 1932, Serial No. 616,424

5 Claims. (Cl. 19—167)

The invention has reference to stop motions for combers or the like.

In the operation of the comber the sliver after passing the detaching rolls passes through the pan and trumpet, and thence through a set of calender rolls with delivery onto a sliver plate. In case the delivery of the sliver through the calender rolls is not normal, as when the sliver becomes reduced in weight, the sliver will tend to accumulate in the pan as the machine continues to run and roller lap around the detaching rolls, causing great inconvenience, to say nothing of loss of material. The light weight sliver delivered onto the sliver plate will also have to be detached and thrown away. To obviate these difficulties it becomes imperative that the machine be automatically stopped immediately upon the running of any light weight sliver through the calender rolls, and this is the essential purpose of the invention; in other words, to provide a stop motion that will immediately stop the machine upon any tendency of the sliver to run through the calender rolls when light in weight.

As will presently be explained the initial moving force for operating the stop mechanism when the sliver runs light in weight through the calender rolls is the dropping of the top one of these rolls. In this connection the use of ordinary smooth-faced rolls cannot well be employed for the following reason: In the first place the top roll must rest upon the sliver as it passes between the rolls. The top roll must be one of considerable weight in order to get sufficient frictional grip upon the sliver to properly draw it through the trumpet. If the top roll be of considerable weight it tends to flatten the sliver thereby leaving very little opportunity for the top roll to drop in sufficient amount to positively actuate a stop mechanism. Not only this but if the sliver be flattened by the top roll the result is that the sliver will be crushed by the action of the rolls and will be delivered on to the sliver plate more or less flattened out and compacted when it should be delivered on to the sliver plate in a soft rope-like body as fluffy as possible but so that it will move along the sliver plate without breaking.

In consequence of these conditions, a further object of the invention is to provide a calender roll construction in which considerable latitude in drop will be afforded the top one of the calender rolls for positively operating the stop motion when the sliver runs light in weight between the rolls, and this under conditions where the

top roll is resting with its full weight upon the sliver; at the same time providing a construction in which the calender rolls will firmly grip the sliver for drawing it through the trumpet, and will deliver the sliver onto the sliver plate in a proper, soft and fluffy state.

A further object of the invention is to provide a stop motion by which the machine will be stopped should abnormal conditions occur at any one of a series of points. The comber is customarily provided with a number of heads, each head having its own set of calender rolls through which a sliver is being delivered. Sometimes the combers are made with independent sets of heads oppositely arranged with lines of calender rolls located at opposite sides of the machine. The object is to provide a stop motion which will become operative in case abnormal conditions occur at any one set of calender rolls however remotely they may be located in the machine.

The invention can best be seen and understood by reference to the drawings where an embodiment thereof is shown, such portion of the machine only being shown as is necessary for a proper understanding of the invention.

Figure 1 is a view mainly in side elevation of various operating parts.

Fig. 2 is a section on the line 2—2 of Fig. 1.

Fig. 3 is a plan of a detail of construction.

Fig. 4 is a cross section of one of the sets of calender rolls and parts immediately adjacent thereto, and

Fig. 5 is a side elevation in fragmentary part of one of the calender rolls.

Referring to the drawings:

1 represents the frame of the machine as the parts thereof occur in the drawings. 2 are the detaching rolls, 3 the pan, 4 the trumpets, 5 and 6 the calender rolls, and 7 the sliver plate. 8 is the sliver.

As the sliver issuing from the trumpet passes between the calender rolls, the top one 5 of these rolls resting upon the sliver will be elevated thereby with relation to the bottom roll, and this by the thickness of the sliver. Should the sliver lessen in weight, the top roll no longer being supported by a sliver of normal body will drop and it is the dropping of this roll as previously explained which is availed of as the initial moving force for operating the stop mechanism. In order that the top roll under such conditions may have a drop ample to positively operate the stop mechanism and to meet all other conditions as previously referred to, provision is made as follows:

Each of the calender rolls is a fluted roll, its

surface being provided with interdental spaces 10 and between these spaces projections 11. The interdental spaces are much wider than the width of the projections and are made quite deep. They 5 present rounding bottom faces 12 curved in cross section. The projections 11 present rounding ends 13 preferably of a curvature corresponding with the curvature presented by the bottom faces 12 of the interdental spaces. The sides of the 10 projections are more or less flattened or even preferably slightly contracted with relation to their ends so that on bringing the rolls together with the projection on one roll centrally located within an adjacent interdental space on the other roll the sides of the projection will lie appreciably removed from the sides of the interdental space 15 within which the projection is contained. The effect is that when the rolls are co-operating and the sliver is passing between the rolls the projections on one roll will enter and press the sliver into the interdental spaces on the other roll causing 20 abrupt bends in the sliver passed between the rolls even though the sliver be of considerable body and weight thus enabling projections on the 25 respective rolls to overlap and the body of the sliver to be gripped between the overlapping projections at a plurality of points. (See Fig. 5.) The top calender roll need only be of sufficient weight to cause the bends in the sliver. In consequence even though the top roll be a relatively 30 light roll it will be driven by the bottom roll, requiring no positive drive of its own and the two rolls will secure a firm grip upon the sliver for drawing it through the trumpet. In this connection it is preferred that the ends of the projections be slightly widened with slight undercuts 35 15 as these undercuts assist in getting a better grip on the sliver for drawing it through the trumpet. The bearing of the top roll against the sliver will at all times be over a relatively large 40 surface or area and the abrupt bending of the sliver will also assist in the support of the top roll. In consequence the sliver as it comes from the trumpet and passes between the rolls will not be 45 flattened out but will remain of considerable thickness when the sliver is running in normal weight, with the advantage not only that the sliver will be delivered onto the sliver plate in a soft and fluffy state but with the advantage also 50 that the top roll will be held so far elevated by the sliver body that when the sliver becomes unduly diminished in weight the top roll will have ample distance to drop with relation to the bottom roll for operating the stop motion.

55 The bottom one of each set of calender rolls is a driven roll mounted upon a shaft 16 which is turned through geared connections 17 in the operation of the machine. Where a series of aligned 60 sets of calender rolls are employed all the bottom rolls are mounted upon the one shaft 16 and turned by this shaft. The top one of each set of calender rolls is mounted to turn upon a spindle 18 the outer ends of which extend through the slotted ends of boxes 19 on the frame of the machine. At one end the spindle is pivoted by a pin 20 to the slotted end of the box within which it is contained. Arranged beneath the opposite end of the spindle is the turned end 21 of a finger 22 fixed to the arm 23 of a balanced lever 24 65 pivoted at the point 25 to a bracket 26 on the frame of the machine. The top one of each set of calender rolls will be maintained in a normal raised position with relation to its companion roll by the sliver when running with full normal 70 weight between the rolls. With the top roll thus

elevated and the lever 24 then occupying its normal balanced position, the turned end 21 of the finger borne by the lever will occupy a position immediately beneath the end of the spindle so that when the roll drops, as it will drop on any 5 tendency of the sliver to run light in weight, the dropping roll will through the spindle and finger turn the lever so that the outer end 27 of its arm 23 will be projected downwardly.

Arranged beneath the sliver plate parallel therewith and extending in the longitudinal direction thereof, is a movable rod 28 common to all the sets of calender rolls where a series of aligned set of rolls are employed. This rod extends through the bottom projecting ends 29 of the same brackets 26 as support the balanced levers, and the rod is arranged to be longitudinally movable back and forth thereon. Borne by this rod are stops 30. These stops are preferably adjustably secured to the rod each by a pin 31 10 extending through the slot 32 in the stop. The stops occupy a determinate relation to the ends 15 27 of the arms 23 of the balanced levers in the sense that, when the levers are occupying their normal balanced position and the sliver is running with full normal weight through the calender rolls, the ends 27 of the levers will not engage the stops as the rod 28 is moved longitudinally back and forth. In case, however, the end of any balanced lever drops, as it will drop when the 20 lever is turned by the operation of the finger when the sliver runs light in weight, then the end 27 of the lever will engage the adjacent stop. Like 25 action will prevail for all the balanced levers and associated stops where several aligned sets of 30 35 calender rolls are employed.

The rod 28 is longitudinally reciprocated during the operation of the machine by reciprocatory movement imparted to a rod 34 which in its normal position lies alongside the end of the rod 28 40 parallel thereto. The rod 34 is provided at its inner end with an upturned forward extension 35 bent to pass around a pin 36 on the side of the rod 28, and presenting an inclined inner edge 37 in that portion thereof lying between the pin 45 and the main body of the rod. With the rods 28 and 34 thus connected, both rods will be moved back and forth as reciprocatory movement is imparted to the rod 34. If, however, the rod 28 is stopped, as by engagement of the end 27 to any 50 of the balanced levers 24 with any of the stops 30 on the rod 28, with the rod 34 then continuing to reciprocate, thereupon the rod 34 will be lifted as the inclined edge 37 on the end of the rod 34 rides over the pin on the rod 28. The rod 55 40 is reciprocated during the operation of the machine by motion applied to a gear 38 in mesh with a gear 39 mounted upon a shaft 40. Fixed to the same shaft is a cam 41 arranged to turn within a collar 42 on the end of the rod 34. As 60 the cam is turned by the operation of the gears reciprocatory movement will be imparted to the rod 34.

Arranged above the rod 34, preferably at the top of the machine, is a shipper rod 45 for throwing the power on or off. This rod is movable lengthwise within supports 46 connected with the frame of the machine. Associated with this rod and arranged in parallel relation thereto is a rod 47, the two rods being connected by a link 48 65 to be movable in unison. The rod 47 passes through a post 49 fixed to the frame of the machine and arranged upon the rod 47 between the link 48 and the side of the post is a coiled spring 70 50. This spring normally, unless restrained, 75

throws the shipper rod into disengaging position for shutting off the power, the spring being compressed as the shipper rod is reversely moved into an engaging position for throwing on the power. 5 The shipper rod is maintained in an engaging position and the spring 50 under compression by a latch bar 51 secured by a pivot 52 to the end of the link 48 and having within it a notch 53 arranged to engage an edge 54 on the post. On 10 releasing the latch bar from engagement with the post by lifting the end of the bar, the shipper bar will be thrown into a disengaging position for shutting off the power by the compressed spring. The latch bar is lifted for releasing it by mechanism interposed between it and the rod 34, the latch bar being lifted as the rod 34 is lifted. This mechanism comprises a shaft 55 which turns within 15 hangers 56 on the frame of the machine. The shaft 55 is horizontally arranged to turn within a plane just above the horizontal plane occupied by the rod 34. At its outer end the shaft 55 bears a crank 57 connecting with a rod 58 which extends upwardly through a guide 59 on the post 49 and bears upon its top end above the guide a finger 60 which normally occupies a position just 20 beneath the end of the latch bar 51. At its inner end the rod 55 bears a finger 61 angularly downturned with the end of the finger occupying a position just above the rod 34 when this rod is 25 occupying its normal position. The immediate effect of the mechanism is that when the rod 34 is lifted its bearing against the finger 61 will operate to turn the shaft 55 and this, through the crank 57, will lift the rod 58 to disengage the latch bar 51 from the post for shutting off the power. 30

The general operation is as follows: It will be assumed that the shipper rod has been moved to an engaging position, being held by the latch bar 51, and that the machine is in operation. In 40 case the sliver should run light in weight through any one of the sets of calender rolls, thereupon the top roll of the particular set will drop. The dropping of this roll will, through the adjacent finger 22 and balanced lever 23, operate to throw the outer end 27 of this lever into engagement with the adjacent stop 30 on the rod 28, stopping the movement of this rod which prior to such stoppage was reciprocating. The rod 34 will 45 continue to reciprocate and thereupon the rod 34 will be lifted by engagement of its inclined edge 37 with the pin 36 on the rod 28. As the rod 34 is lifted, movement will be imparted through the connecting mechanism which operates to raise the rod 58, thereby releasing the latch bar 51, whereupon the compressed spring will throw the shipper rod into a disengaging position shutting off the power and stopping the machine. It will be observed that the machine is stopped immediately 50 upon the sliver running light in weight for any one of the sets of calender rolls, and this before the sliver has an opportunity to accumulate in the pan lying back of such set of rolls, and before the sliver of lessened weight has had opportunity to travel for any appreciable distance 55 over the sliver plate.

Having thus fully described my invention, I claim and desire to secure by Letters Patent of the United States:—

1. In a stop motion for combers and the like, 70 the combination comprising a set of calender rolls through which the sliver passes, means for mounting the top roll whereby it will drop when the sliver runs light in weight between said rolls and including in part a spindle for said top roll, 75 a reciprocable member, means for reciprocating

said member, a stop borne by said reciprocating member; a lever mounted to normally occupy an out-of-the-way position with relation to said stop, a finger borne by said lever and having an end turned to extend beneath said spindle on the top roll whereby the lever will be turned to engage said stop on the dropping of said top roll, mechanism for stopping the machine, and means whereby said mechanism will be operated on the stopping of said member. 10

2. In a stop motion for combers and the like, a set of calender rolls between which the sliver passes to be fed by said rolls, each of said rolls having an exterior surface provided with deep interdental spaces with projections interposed between said spaces, said spaces being considerably wider than said projections so that on bringing the rolls into mesh with a projection on one roll centrally located within an adjacent interdental space on the other roll the sides of the projection will lie appreciably removed from the sides of the interdental space within which the projection is contained whereby abrupt bends will be formed in the sliver passed between the rolls thus enabling projections on said respective rolls to overlap and the body of the sliver to be gripped between said overlapping projections, and means for mounting one of said rolls whereby it will have relative movement to the other roll when the sliver between said rolls varies in weight. 20

3. In a stop motion for combers and the like, a set of calender rolls between which the sliver passes to be fed by said rolls, each of said rolls having an exterior surface provided with deep interdental spaces with projections interposed between said spaces, said spaces being considerably wider than said projections and presenting rounding bottom faces, said projections presenting rounding ends with relatively flattened sides so that on bringing the rolls into mesh with a projection on one roll centrally located within an adjacent interdental space on the other roll the sides of the projection will lie appreciably removed from the sides of the interdental space within which the projection is contained whereby abrupt bends will be formed in the sliver passed between the rolls thus enabling projections on said respective rolls to overlap and the body of the sliver to be gripped between said overlapping projections and means for mounting one of said rolls whereby it will move relatively to the other roll when the sliver between said rolls varies in weight. 30

4. In a stop motion for combers and the like having mechanism for stopping the machine, a set of calender rolls between which the sliver passes to be fed by said rolls, each of said rolls having an exterior surface provided with deep interdental spaces with projections interposed between said spaces, said spaces being considerably wider than said projections so that on bringing the rolls into mesh with a projection on one roll centrally located within an adjacent interdental space on the other roll the sides of the projection will lie appreciably removed from the sides of the interdental space within which the projection is contained whereby abrupt bends will be formed in the sliver passed between the rolls thus enabling projections on said respective rolls to overlap and the body of the sliver to be gripped between said overlapping projections, a spindle on which said top roll is mounted to turn, means for pivotally supporting said spindle at one end thereof whereby the top roll may move relatively 40

5 to the bottom roll when the sliver between said rolls varies in weight, and mechanism in operative engagement with the free end of said spindle and actuated thereby for operating said mechanism for stopping the machine in response to relative movement of said rolls of a predetermined amount.

10 5. In a stop motion for combers and the like having mechanism for stopping the machine, a set of calender rolls between which the sliver passes to be fed by said rolls, each of said rolls having an exterior surface provided with deep interdental spaces with projections interposed between said spaces, said spaces being considerably 15 wider than said projections and presenting rounding bottom faces, said projections presenting rounding ends with relatively flattened sides so that on bringing the rolls into mesh with a projection on one roll centrally located within

an adjacent interdental space on the other roll the sides of the projection will lie appreciably removed from the sides of the interdental space within which the projection is contained whereby abrupt bends will be formed in the sliver passed between the rolls thus enabling projections on said respective rolls to overlap and the body of the sliver to be gripped between said overlapping projections, a spindle on which said top roll is mounted to turn, means for pivotally supporting said spindle at one end thereof whereby the top roll may move relatively to the bottom roll when the sliver between said rolls varies in weight, and mechanism in operative engagement with the free end of said spindle and actuated thereby for operating said mechanism for stopping the machine in response to relative movement of said rolls of a predetermined amount.

JOSEPH FOSSEL.
